US00D732002S

(12) **United States Design Patent**
Goransson

(10) **Patent No.:** **US D732,002 S**
(45) **Date of Patent:** **** Jun. 16, 2015**

(54) **HEADSET**

(71) Applicant: **GN Netcom A/S**, Ballerup (DK)

(72) Inventor: **Magnus Goransson**, Dalby (SE)

(73) Assignee: **GN Netcom A/S** (DK)

(**) Term: **14 Years**

(21) Appl. No.: **29/488,803**

(22) Filed: **Apr. 23, 2014**

Related U.S. Application Data

(62) Division of application No. 29/429,785, filed on Aug. 16, 2012, now Pat. No. Des. 706,244.
